FOREIGN PATENT DOCUMENTS

EM 007147178-0001 * 10/2019

Primary Examiner — Paula Allen Greene

(57) **CLAIM**

The ornamental design for an earphone, as shown and described.

DESCRIPTION

FIG. 1 is a front elevation view of an earphone showing my new design;

FIG. 2 is a rear elevation view thereof;

FIG. 3 is left side elevation view thereof;

FIG. 4 is a right side elevation view thereof;

FIG. 5 is a top plan view thereof; and,

FIG. 6 is a bottom plan view thereof.

The broken lines depict environment that forms no part of the claimed design.
